(57) **CLAIM**

The ornamental design for a golf putting aid as shown and described.

DESCRIPTION

FIG. 1 is a top perspective view of a golf putting aid according to the invention;

FIG. 2 is a bottom perspective view of the golf putting aid of FIG. 1;

FIG. 3 is a front view of the golf putting aid of FIG. 1;

FIG. 4 is a rear view of the golf putting aid of FIG. 1;

FIG. 5 is a top view of the golf putting aid of FIG. 1;

FIG. 6 is a bottom view of the golf putting aid of FIG. 1;

FIG. 7 is a left side view of the golf putting aid of FIG. 1; and,

FIG. 8 is a right side view of the golf putting aid of FIG. 1. The broken lines shown in FIGS. 1, 2, 5 and 6 are for illustrative purposes only and form no part of the claimed design.

1 Claim, 4 Drawing Sheets
